UNITED STATES PATENT OFFICE

2,518,780

APPARATUS FOR PREVENTING FLY FROM
DEPOSITING ON THE DRIVE MEMBERS OF
TEXTILE MACHINESHeinrich Hess, Winterthur, Switzerland, assignor
to Aktiengesellschaft Joh. Jacob Rieter & Cie.,
Winterthur, SwitzerlandApplication July 27, 1948, Serial No. 40,844
In Switzerland August 26, 1947

2 Claims. (CL 57—56)

1

Textile machines naturally will become covered with dust in operation. Preferably the most essential drive members of the machine, which are assembled in the drive head, should be hooded to the outside as fully as possible. A complete enclosure or sealing of the drive head, however, is not possible since the said head is operatively connected with the machine proper and certain members which translate the movement have to be adjusted slots provided in the cowling. As the rotating machine members produce air currents, the ingress of dust and fly through the apertures present in the cowling is undesirably increased.

The method according to my present invention eliminates the said deficiencies in that the air in the hooded drive head of the machine is subject to a pressure higher than the atmospheric pressure. Air thus will constantly flow to the outside through the apertures in the hood. Dust and fly, thus, is prevented from reaching the inside of the hooded machine drive-head, and, further, the drive-head members which become heated by friction are constantly cooled by air, which feature is very desirable. The said protective and cooling features contribute a great deal to a reliable operation of the machine, and, further, the maintenance of the latter is facilitated.

A fan, advantageously mounted inside the hood on a drive shaft of the machine and which sucks the air through a screened opening in the hood, suitably is used as a means for raising the air pressure inside the hood.

The method according to my present invention is explained, by way of example, by means of the partly schematic drawing which illustrates one example of the means for carrying into effect the said method, which means also form part of my present invention.

In the drawing, the drive head of a spinning machine is shown in vertical section.

The hood comprises a sheet member 1 which covers the machine drive-head on the end face and on top, and which is secured on the machine side to the end shield 2 of the spinning frame and, on the rear side, to a rear wall 3, the front wall being omitted. An electric motor 4, disposed in the drive head in a manner known per se, is operatively connected to the machine main shaft 8 through the belt drive 5—7. The main shaft 8 is rotatably mounted in the shield 2 and on a support or prop 9, and drives all the operating members of the machine through means not shown.

2

A fan 10 is secured to the overhung end of the main shaft 8 inside the hood, in close proximity to a suction opening in the end wall of the hood 1. The said opening is spanned by a wiremesh screen 11. The shield 2 is slotted at the points of passage of the rolls 12 of the draw-head, in order to provide adjustability of the grip or spacing between the rolls 12. The shield 2, further, has a recess 13 in the range of passage 10 of the drive drum 14 of the spinning spindles into the drive head, in order to permit the said drum to move bodily up and down during the spinning process.

When the spinning machine is in operation, 15 the fan 10 secured to the main shaft 8 is rotated and sucks air through the screen 11 from the outside into the drive head so that a slight excess pressure is built up in the hooded head. The air escapes from the latter through all the openings where moving members of the machine pass through the hood, for example, the slots where the rolls 12 and the drive drum 14 pass into the hood.

The excess pressure in the machine drive head 25 is built up to such value that the air flows out of the hood at moderate velocity so as not to impair the spinning operation. Such pressure, however, is sufficient to positively keep out all impurities from the machine members inside the drive-head hood.

30 What I claim as new and desire to secure by Letters Patent, is:

1. Apparatus for preventing the settling of dust and waste on the driving heads of textile machinery, comprising a casing closing off said operating parts of the driving heads from the outside, said casing being provided with openings for the passage of power transmission members for driving the textile machinery, a fan in the 35 space enclosed by said casing, a drive shaft for the fan said casing having an opening for ingress of air, an air filter covering said air ingress opening, said fan being located adjacent said air opening for drawing air through said opening and filter into the casing under a pressure higher than atmospheric so that a continuous outflow of air will take place from the shaft openings in the casing so as to prevent dust and waste from entering the casing.

2. Apparatus for preventing the settling or accumulation of dust and waste on the operating parts of driving heads of textile machinery, comprising a casing closing off said operating parts of the driving heads from the outside, said casing being provided with openings for the passage

of power transmission members for driving the textile machinery, means for introducing air into said casing to create in said casing a pressure somewhat higher than atmospheric so that a continuous outflow of air will take place from the shaft openings in the casing so as to prevent dust and waste from entering the casing, and means for cleaning the air before introduction into the casing.
